UNITED STATES PATENT OFFICE.

WILLIAM F. HELMOND, OF HARTFORD, CONNECTICUT, ASSIGNOR TO UNDERWOOD TYPEWRITER COMPANY, OF NEW YORK, N. Y., A CORPORATION OF DELAWARE.

TYPE-WRITING MACHINE.

1,302,161.

Specification of Letters Patent. Patented Apr. 29, 1919.

Application filed May 18, 1917. Serial No. 169,448.

To all whom it may concern:

Be it known that I, WILLIAM F. HELMOND, a citizen of the United States, residing in Hartford, in the county of Hartford and 5 State of Connecticut, have invented certain new and useful Improvements in Type-Writing Machines, of which the following is a specification.

This invention relates to an improvement 10 in type-writing machines, and more especially to a work-gage and holder for wrapping a stiff work member around the platen.

One of the objects of this invention is to form a card-guide and holder in a single 15 piece, which may coöperate with a gage to properly position a card on the platen.

Gage elements and the card-holder are mounted floatingly and connected to the case-shift frame, so as to maintain the same 20 relation with respect to the printing line of the platen in both upper and lower-case positions of the platen. The floating frame for the gage and holder is guided in its vertical movements by having a pair of flanged 25 rollers projecting in slots provided on the floating frame, thus preventing the parts from getting out of alinement by a movement lengthwise of the platen. The flanged rollers are mounted on spring brackets fixed 30 on the type-bar segment, so that they maintain the gage and holder yieldingly against the platen for all positions of vertical movement. This necessitates a loose pivotal 35 mounting or open bearing of the floating frame on the case-shift frame, allowed for by holding the floating frame on its pivot by means of its spring. In this way, the device may be quickly assembled and is quite flexible.

40 The card-holder itself has a loose open pivot, or, in other words, it is merely fulcrumed in grooved brackets, so as to be swung between an operative position in close juxtaposition to the platen, and to an 45 inoperative position forward and clear of the platen. Springs are provided for maintaining a card-guide on the brackets, and act to lock the card-holder automatically in either of its adjusted positions. The locking 50 action of the springs is aided by a pair of rounded studs, with which lower ends of the card-guide and holder engage alternately on the front and rear sides thereof, according to the position of the card-guide 55 and holder in coöoperative relation with the

platen, and away from the platen, respectively.

The card-holder is preferably formed of a single strip of metal cut out and stamped up to the proper contour, so as to form a 60 light simple structure easily manufactured. It includes a pair of V-shaped prongs, which arch from the back surface of the holder toward the platen, so as to guide the leading edge of the card as it comes around the 65 platen. The gage is provided with a projection extending upwardly from the scale edge of the gage, so as to coöperate with one of the prongs, and insures an almost continuous surface against which the leading 70 edge of the card may cam, so as to properly guide it around the platen.

Other features and advantages will hereinafter appear.

In the accompanying drawings,

75 Figure 1 is a vertical section, taken from front to rear, with parts omitted to simplify the showing, and illustrating the card-holder and guide as in its position coöperating with the platen.

80 Fig. 2 is a skeleton perspective view, showing the way in which the card-holder and gage are mounted to move with the case-shift frame.

85 Fig. 3 is an enlarged detail view, in front elevation, showing the card-holder in its rearmost position coöperating with the platen.

90 Fig. 4 is a view, looking at it from the right side, with parts in section, and showing the card-holder in coöperation with the platen, but in its upper-case position corresponding to the upper-case position of the platen.

95 Fig. 5 is an enlarged detail view, partly in section on line 5—5, Fig. 3, and showing the card-holder as swung away from the platen to an inoperative or idle position.

100 Numeral keys 1 and alphabet keys 2 depress key levers 3 to rock bell cranks 4, so as to swing type-bars 5 up rearwardly against the front side of a platen 6, mounted to rotate on a carriage 7. The carriage 105 has the usual step-by-step movement at the actuation of the character keys under the control of an escapement mechanism, indicated in general at 8. Each of the type-bars 5 has two characters 9 and 10, corresponding to writing of lower and upper-case characters,

110

To enable the change in writing from normal lower-case characters to upper-case characters, the platen 6 is mounted in a platen frame 11, which, in turn, is supported 5 for vertical movement by means of arms 12, pivotally mounted on the carriage 7. The platen frame 11 rides by means of traveling rollers 13 on a shift rail 14. The shift rail 14 is mounted on a shift frame 15, pivoted 10 at 16. To rock the shift frame 15, and thus raise the platen 6 for upper-case writing, there are provided two keys 17, one of which may be used for temporary shift and the other for semi-permanent shift. These keys 15 are provided with the usual levers 18, which, when the associated keys are depressed, are rocked individually to swing forward arms 19. Each of these arms bears against one 20 of the sides of the shift frame 15 at the rear thereof. In this way, the shift frame 15 is rocked in a clockwise direction to raise the platen 6.

For the purpose of properly positioning a work member, such as a stiff card, on the platen 6, there is provided a gage 20 and a card-holder and guide 21. In order that these two elements may coöperate properly with the platen 6 in both lower and upper-case positions of the latter, they are supported 25 on a floating frame 22. The floating frame 22 is, in turn, supported on the case-shift frame 15. For this purpose, the floating frame 22 is formed of a cross-piece 23, on which the gage 20 and the card-holder 30 and guide 21 are mounted in the manner to be described, and side arms 24. The side arms 24 extend downwardly from the cross-piece 23, and arch rearwardly along the shift rail 14 and engage pivots 25 in the 35 form of studs mounted on the case-shift frame 15. To engage the pivot studs 25, the side arms 24 are provided with open bearings 26, whereby the floating frame as a 40 whole may be readily slipped onto the studs 45 and will allow a certain amount of lost motion.

In order to hold the floating frame 22 on the pivot studs 25 there is provided on each side a spring 27, which engages a pin 28 50 fixed on the shift frame 15, and at the other end engages a stud 29 fixed on the corresponding arm 24 of the floating frame. It will be noted that the studs 29 are located on projections 30 of the arms 24, which 55 extend somewhat to the rear and below the pivot studs 25. This will tend to hold the floating frame 22 and the parts carried thereby in proper position to coöperate with the platen 6.

60 In order to insure the proper vertical movement of the floating frame 22 with the case-shift frame, it is guided for vertical movement. For this purpose there are provided on the cross-piece 23 of the floating frame 22, a pair of guiding brackets 31, pro-

jecting upwardly from the cross-piece and having guiding slots 32 therein. Guiding rollers 33 are each provided with a radially-extending circular flange 34, which projects from the body of the rollers into the guiding slots 32. The guiding rollers 33 are fixed so that the floating frame 22 may have a certain amount of vertical movement relative thereto, and still be held against a movement lengthwise of the platen. The 70 body portion of the rollers do not project through slots 32, but rest on brackets 31, so as to prevent forward movement of the guiding frame, and thus hold indirectly the gage and card-holder in close juxtaposition 75 to the platen. In order that a certain amount of yielding may be provided for this guiding and constraining action, the rollers 33 are pivotally mounted on spring brackets 35, which are normally under a slight tension tending to force the floating frame and the parts carried thereby toward the platen 6. The brackets 35 are fixed on a type-segment 80 85 90 95 100 105 110 115 120 125 130 135 140 145 150 155 160 165 170 175 180 185 190 195 200 205 210 215 220 225 230 235 240 245 250 255 260 265 270 275 44 between them. In other words, the legs of the card-guide and holder 21 extend on the outside of the brackets 44, and are provided with inwardly-extending shoulders 55 to engage the fulcrums formed by the apex of the notches 47 in the brackets 44.

In order to hold the card-guide and holder 21 in position on the brackets 44, there are provided a pair of springs 49 secured to the holder 21 at one end, and to a pin 50 at their other end. It will be seen that this permits a certain amount of back and forth swinging movement of the card-guide and holder 21 from the idle position seen at Fig. 5 to the active position of Fig. 1. This shift of the holder 21 must, however, be done forcibly, as the springs 49 are extended from the pin 50 to the holder 21 in such a way as to lock the holder in both its idle and active positions, by passing beyond a dead center.

In order to assist in this locking, the lower ends of the legs engage rounded studs 51 provided on the shelves 45. The legs of the holder 21 pass alternately from position 25 in rear of the studs to position in front of the studs, when the upper edge of the guide and holder 21 will swing oppositely to an active position in engagement with the platen and to an idle position away from the platen respectively.

For preventing the accidental disengagement of the card-guide and holder 21 from the notches 47 on the brackets 44, when it is moved quickly to an idle position, the 35 rear sides of the notches 47 are indented at 52 to form shoulders in a position to be engaged by the shoulders 48 on the legs of the holder 21. When the force shifting the holder is discontinued, the spring 49 will 40 automatically settle the holder to its proper position.

The card-holder and guide 21 is formed of a single sheet of metal cut out to give the necessary contour and having its edges 45 flanged up to give the desired amount of rigidity with a lightness of structure. In addition to the legs mentioned above, the card guide and holder has a top cross-piece 53 provided with a forwardly extending 50 finger-piece 54, by which the card-holder as a whole may be manipulated.

Projecting downwardly from the top cross-piece 53, there are provided a pair of prongs 55, spaced from each other on opposite sides of the printing point of the typewriter. These prongs have their side edges flanged up to give a certain amount of rigidity for the lightness of their structure. The lower pointed ends or apexes of the prongs 60 are bent rearwardly toward the platen, as seen more clearly at Fig. 1, so as to conform somewhat to the curvature of the platen, and in this way properly warp a stiff card around the platen.

65 The gage 20 has projecting upwardly

from one of its scale plates 38 an extension 56, which goes in behind one of the prongs 55, so as to form a practically continuous surface, with which the leading edge of the stiff card may engage in its movement to 70 a proper position around the platen 6.

To assist the gage 20 and the guide and card-holder 21 in properly maintaining a work member on the platen 6, there is provided a pair of rollers 57 which take the 75 card or other work member as it comes from the holder 21 and guides it around the platen. The rollers 57 are mounted on a rod 58, so as to be quite close to the top edge of the guide and card-holder 21. The rod 58 80 forms a part of a swinging bail 59, so that it may be moved between operative and inoperative position into engagement and out of engagement with the platen, respectively. The sides of the bail 59 extend forwardly 85 of their pivot points 60 to conform with the sides of the platen frame 11, then inwardly a sufficient distance to avoid the normal overhead pressure rollers 61 when the latter are shifted out of the way to the side, and then downwardly at 62 to form supports for the rod 58. The rollers 57, it will be noted by reference to Fig. 2, are thus supported in axial alinement with the normal overhead pressure rollers 61.

95 The utility of the device will be readily understood when taken in connection with the above description. When the card-holder is not in use, it is shifted to the Fig. 5 position, where it will be clear of the 100 platen. In this position, it is locked by the springs 49, so that it will be practically rigid. To bring the card-holder into play, it is merely necessary to lift it slightly 105 against the tension of the springs, so that the side legs clear the studs 51, and swing the holder in toward the platen. The springs 49 will automatically settle the holder in its proper position in close relation with respect to the platen. It will then 110 coöperate with the gage 20 to warp a stiff card snugly around the platen. When the platen is shifted to write upper-case characters, the gage and holder will move with the platen to maintain substantially the 115 same relation, so that the card will always be automatically held and guided on the platen 6.

Variations may be resorted to within the 120 scope of the invention, and portions of the improvements may be used without others.

Having thus described my invention, I claim:

1. In a typewriting machine having a main framework, the combination with a 125 carriage and a platen thereon, of a support located upon said framework in juxtaposition to said platen to remain stationary during the travel of the platen, a holder loosely fulcrumed on said support and rocking for- 130

wardly and backwardly between operative and inoperative positions near and away from said platen, and two-way acting springs maintaining said holder on said support and automatically locking it in both its positions of adjustment.

2. The combination with a platen, of a support located in juxtaposition to said platen, a pair of notched brackets on said support, a holder resting in the notches of said brackets, and springs for preventing said holder from coming out of said notches.

3. The combination with a platen, of a pair of notched brackets located in juxtaposition to said platen, and a holder straddling said brackets and having shoulders projecting into said notches, so as to fulcrum said holder on said brackets.

4. The combination with a platen, of supporting brackets, and a card-holder straddling said brackets, said card-holder including legs projecting down to the outsides of said brackets and prongs projecting interiorly of said holder and rearwardly of the back face thereof, so as to conform somewhat to the curvature of said platen.

5. The combination with a platen, of supporting brackets, a card-holder straddling said brackets, said card-holder including legs projecting down to the outsides of said brackets and prongs projecting interiorly of said holder and rearwardly of the back face thereof, so as to conform somewhat to the curvature of said platen, and a gage having an extension overlapping one of said prongs vertically, so as to form a practically continuous surface for guiding the leading edge of the work-member around said platen.

6. The combination with a platen, of means for enabling the proper adjustment of a work-member on said platen, case-shift mechanism for said platen, a support mounted for movement with said case-shift mechanism and said platen, and acting to maintain said means in substantially the same relation to said platen for both upper and lower-case writing, and guiding rollers for said support justifying the position of said support and the parts carried thereby.

7. The combination with a platen, of means for enabling the proper adjustment of a work-member on said platen, case-shift mechanism for said platen, a support for said enabling means mounted on said case-shift mechanism for movement therewith, and guiding means for preventing movement of said support lengthwise of said platen comprising a slotted bracket on said support, and a stationary roller projecting into the slot of said bracket.

8. The combination with a platen, of means for enabling the proper adjustment of a work-member on said platen, a support for said means, case-shift mechanism connected to simultaneously adjust said platen

and said support, a pair of brackets on said support, guiding rollers engaging said brackets, and spring brackets for said rollers maintaining said rollers in proper position and maintaining said means in proper relation with said platen.

9. The combination with a platen, of means for maintaining a work-member in proper position on said platen, case-shift mechanism for said platen, and a support mounted on said case-shift mechanism, and having an open pivotal bearing on said case-shift mechanism.

10. The combination with a platen, of means for enabling the proper adjustment of a work-member on said platen, case-shift mechanism for said platen, a support for said means having an open pivotal bearing on said case-shift mechanism, guides for said support, and springs for said support, said guides and said springs coöoperating to adjust said support, so as to maintain said means in proper relation with said platen for both upper and lower-case writing.

11. The combination with a platen, of means for enabling the proper adjustment of a work-member on said platen, a floating support for said means having a pair of slotted brackets thereon, a pair of rollers having circumferentially projecting flanges extending into said slots to guide said support and the means carried thereby, and spring means for forcing the body portion of said rollers into engagement with said brackets, to maintain said means in proper relation with respect to said platen.

12. The combination with a revoluble platen and a shift frame by which said platen is shiftable up and down, of a frame hinged upon said shift frame and having a card-holding surface to bear upon the front of the platen, and a pair of spring rollers, one at each side of the printing point, to press said surface of said frame against the front of the platen; said rollers mounted upon the stationary framework to roll upon said frame at the shifting of the platen.

13. The combination with a revoluble platen and a shift frame by which said platen is shiftable up and down, of a frame hinged upon said shift frame and having a card-holding surface to bear upon the front of the platen, a pair of spring rollers, one at each side of the printing point, to press said surface of said frame against the front of the platen; said rollers mounted upon the stationary framework to roll upon said frame at the shifting of the platen, an auxiliary card-holder loosely mounted upon said hinged frame to bear against the platen above the printing point, and a spring between said auxiliary card-holder and said hinged frame to press the auxiliary card-holder upon the platen.

14. The combination with a revoluble

- platens and a shift frame by which said platen is shiftable up and down, of a frame hinged upon said shift frame and having a card-holding surface to bear upon the front 5 of the platen, and a pair of spring rollers, one at each side of the printing point, to press said surface of said frame against the front of the platen; said rollers mounted upon the stationary framework to roll upon 10 said frame at the shifting of the platen, said hinged frame being mounted by open bearings upon said shift frame, and said rollers being mounted below the point of contact of said hinged frame surface with 15 the platen, but above said open bearings, to hold the latter against dislocation.
15. The combination with a revoluble platen and a shift frame by which said platen is shiftable up and down, of a frame 20 hinged upon said shift frame and having a card-holding surface to bear upon the front of the platen, a pair of spring rollers, one at each side of the printing point, to press said surface of said frame against the front of 25 the platen; said rollers mounted upon the stationary framework to roll upon said frame at the shifting of the platen, an auxiliary card-holder loosely mounted upon said hinged frame to bear against the platen 30 above the printing point, and a spring between said auxiliary card-holder and said hinged frame to press the auxiliary card-holder upon the platen; said springs connected to said auxiliary card-holder to hold 35 it either back against the platen or forwardly away therefrom.
16. In a typewriting machine having a main framework, a carriage to travel thereon, and a platen upon said carriage, the 40 combination with a card-holder mounted upon the main framework, and means for pressing the card-holder against the platen, said card-holder arranged about at the printing line of the platen, of an auxiliary 45 card-holder, and a support upon the main framework for said auxiliary card-holder, said auxiliary card-holder extending upwardly to bear upon the platen above the printing line.
- 50 17. In a typewriting machine having a main framework, a carriage to travel thereon, and a platen upon said carriage, the combination with a card-holder mounted upon the main framework, and means for 55 pressing the card-holder against the platen, said card-holder arranged about at the printing line of the platen, of an auxiliary card-holder, a support upon the main frame- work for said auxiliary card-holder, said auxiliary card-holder extending upwardly to bear upon the platen above the printing line, and means upon said support to hold said auxiliary card-holder forwardly away 60 from the platen.
18. In a typewriting machine having a main framework, a carriage to travel thereon, and a platen upon said carriage, the combination with a card-holder mounted upon 65 the main framework, and means for pressing the card-holder against the platen, said card-holder arranged about at the printing line of the platen, of an auxiliary card-holder, and a support upon the main framework for said auxiliary card-holder, said auxiliary card-holder extending upwardly from said support to bear upon the platen above the printing line and in the form of an inverted U-frame having at its upper 70 portion a depending card-guiding projection.
19. In a typewriting machine having a main framework, a carriage to travel thereon, and a platen upon said carriage, the 75 combination with a card-holder mounted upon the main framework, and means for pressing the card-holder against the platen, said card-holder arranged about at the printing line of the platen, of an auxiliary card-holder, a support upon the main framework for said auxiliary card-holder, said auxiliary card-holder extending upwardly from said support to bear upon the platen above the printing line and in the form of an inverted U-frame having at its upper 80 portion a depending card-guiding projection, and springs connected to said auxiliary card-holder to hold the card-holder against the platen.
20. The combination with a card-holder and means for pressing it against the platen, said card-holder arranged about at the printing line of the platen, of an auxiliary 85 card-holder, a support for said auxiliary card-holder, said auxiliary card-holder extending upwardly to bear upon the platen above the printing line and in the form of an inverted U-frame having at its upper portion a depending card-guiding projection, and springs to engage the legs of said U-frame to hold the card-holder against 90 the platen.
